Des. 196,873
Patented Nov. 12, 1963

196,873

VENDING MACHINE PANEL

Walter L. Koch, Wheaton, Ill., assignor to Automatic
Canteen Company of America, Chicago, Ill., a corpo-
ration of Delaware

Filed Nov. 9, 1961, Ser. No. 67,452

Term of patent 14 years

(Cl. D52—3)

FIG. 1

FIG. 2

FIG. 3

FIGURE 1 is a perspective view of a vending machine panel taken from the front and one side thereof, showing my new design;

FIGURE 2 is a side elevational view thereof; and

FIGURE 3 is a top plan view thereof.

The undisclosed right side of said panel is substantially the same in appearance as the side shown.

The rear of said panel is flat and plain.

The dominant features of my design reside in the portions shown in full lines.

I claim:

The ornamental design for a vending machine panel, as shown and described.
